Assignor to

Lowell Manufacturing Company

Letter's Patent No. 2452, Dated Sept 25, 1866

Design for a Carpet Pattern.

The Schedule referred to in these Letters Patent and making part of the same.

To all whom it may concern:

Be it known that I, Eleazar J. May of Lowell in the County of Middlesex and State of Massachusetts, have originated and designed a new Pattern for carpets, or other fabrics, of which the following is a full, clear and exact description, reference being had to the accompanying drawing making part of this Specification.

A, A, are quarters of an irregular shaped Figure resting on Sprig Work B, B, and enclosing three little Flowers. — C, C, are quarters of an irregular shaped Figure, as shown in the drawing, resting on a Wreath of Flowers and Leaves.

The colors employed for the different portions of the Design, may be varied to suit the taste and wish of the manufacturer.

Claims. — What I claim as my invention and desire to secure by Letters Patent is,

The Design or Pattern for carpets or other fabrics, herein set forth.
